UNITED STATES PATENT OFFICE.

DANIEL F. LEPLEY, OF CONNELLSVILLE, PENNSYLVANIA.

STOP-LATCH-TRIPPING MECHANISM.

1,403,124.

Specification of Letters Patent. Patented Jan. 10, 1922.

Application filed January 22, 1921. Serial No. 439,205.

To all whom it may concern:

Be it known that I, DANIEL F. LEPLEY, a citizen of the United States, residing at Connellsville, in the county of Fayette and 5 State of Pennsylvania, have invented a new and useful Stop-Latch-Tripping Mechanism, of which the following is a specification.

This invention relates to stop latch tripping mechanism for use in controlling the movement of cars to cages, rotary dumps, and the like.

One of the objects of the invention is to provide simple and efficient means which 15 will operate automatically to stop a train of cars after a predetermined number of cars of the train have been directed onto the cage or dump, said means being readily adjustable to release a desired number of 20 cars, and operating efficiently to stop the remaining cars.

Another object is to provide apparatus of this character which is simple in construction, will not readily get out of order 25 and is automatic in its operation after being shifted to release the engaged car of the train.

With the foregoing and other objects in view which will appear as the description 30 proceeds, the invention consists of certain novel details of construction and combinations of parts which will be hereinafter more fully described and pointed out in the claims, it being understood that various 35 changes may be made in the construction and arrangement of the parts without departing from the spirit or sacrificing any of the advantages of the invention as set forth in the appended claims.

40 In the accompanying drawings the preferred form of the invention has been shown.

In said drawings—

Figure 1 is a side elevation in diagram of 45 the stop latch and its tripping mechanism combined with a rotary dump.

Figure 2 is a plan view in diagram of the structure shown in Figure 1.

Figure 3 is a side elevation of the stop 50 latch and its tripping mechanism.

Figure 4 is a section on line 4—4, Figure 3.

The present improvements are to be used with a rotary dump A of any standard type or, if preferred, a dumping cage can be 55 used in lieu thereof. Located adjacent the rotary dump is a rod actuating engine E

which can be of the same general type as that shown in Patent 1,183,306 issued to me on May 16th, 1916. This engine need not, it is thought, be described in detail but it 60 may be stated that it includes cylinders containing pistons, not shown. A three-way piston valve V is provided, for controlling the action of the engine. This valve is controlled by a lever 1 having a depending arm 65 2. A rod R operated by the piston in the engine E is connected to crank arms A' secured to spaced shafts A'' extending laterally from under the track T on which the cars travel toward the rotary dump. An 70 arm B extends from each shaft A'' and is connected by a link B' to a horn or chock H pivotally mounted and so positioned that, when raised by the toggle formed by arm B and link B', it will extend into the 75 path of one of the wheels of a car C and hold the car against forward movement along the track toward the dump. It is to be understood that the two horns H are arranged in pairs for the front wheels of the 80 cars adjacent thereto and that each horn has an arm B and link B' for operating it. The horns and their operating means constitute, in themselves no part of the invention but have already been disclosed in Patent No. 85 1,233,070 issued to me on July 10th, 1917.

For the purpose of shifting the valve lever 1 to reverse the pressure in the cylinders and lower the horns H, thereby to release the cars, a novel form of automatically 90 operating mechanism is provided. This mechanism includes a shaft disposed at right angles to the track T, between the two sets of stop mechanism, as shown at 3 and secured to this shaft is a weighted arm 3'. 95 A tripping arm 4 is supported close to the track T where it will be successively contacted and lowered by the wheels of the cars coupled together in a train. The arm 4 is as long as the wheel base of a car but 100 shorter than the distance between the rear wheels of one car of a train and the front wheels of the next following car of said train. A crank arm 5 is secured to the shaft 3 and has a cable 6 extending upwardly therefrom over guide sheaves 7 suitably supported and thence downwardly to a rack 8 which is slidably mounted on a suitable support 9 and has a longitudinal series of ratchet teeth 10. Another rack 11, 110 which is stationary, is located at the side of the movable rack or bar 8 and the teeth

on both racks are located side by side and adapted to be engaged by pawls 12 pivotally connected to one end of a lever 13. A cable 14 is connected to the other end of the lever 13 and extends over suitably supported guide sheaves 15 and thence downwardly to an arm 16 on lever 1. Another cable 17 extends from the lower end of the arm 2 of lever 1 and is connected to the pawls 12, as shown, so as to draw them out of contact with the rack teeth when lever 1 and connected mechanism are shifted to raise the horns H to holding positions to stop cars as hereinafter described. This cable 17 has sufficient slack in it to permit the lever 16 and its arm 2 to turn sufficiently to operate the horns or chocks before disengaging the pawls.

When the apparatus is in use a train of cars C is caused to gravitate toward the point of delivery while the horns H are in lowered or released positions. If two cars are to be supplied to the dump to be unloaded simultaneously a slack, for example, of eight inches is left in the cable 14 and a slack of four inches is left in the cable 17. When the first car of the train approaching the delivery point passes over the lever 4 it depresses the lever and holds it depressed until the car passes thereover. During this depression of the lever it pulls through the cable 6 upon the bar 8 so that the teeth 10 engaging one of the pawls 12 will move said pawl upwardly a sufficient distance to take up four inches of the slack in cable 14 and part of the slack in the cable 17. As the train of cars C continues to move forward the first car comes to position above the horns H while the second car depresses the lever 4 so as to again pull through cable 6 upon the bar 8 and take up the remaining four inches of slack in the cable 14 and the balance of slack in the cable 17. During each of these upward movements of the bar 8 the other pawl slips over some of the teeth of the stationary bar 11 and is held by said teeth against downward or return movement. Likewise each time the arm 4 is released by the car passing thereover the bar 8 gravitates to its initial position and raises the arm 4 assisted by a weighted arm 18 extending from the shaft 3. As the second car moves forward after depressing the arm 4 it moves to position above the horns H and the first car advances to position close to the point of delivery. Just as the first car of the train reaches this position the third car of the train comes against and depresses the lever 4 so as to pull through cable 6 upon the bar 8 and again elevate it. This movement is sufficient to pull through the lever 13 and cable 14 upon the short arm 16 so as to cause the lever 2 to swing and reverse the valve mechanism whereby pressure is promptly applied to the pistons in the engine E to

move the rod R and elevate the horns H into the path of the front wheels of the second and fifth cars of the train. This final upward movement of the bar 8 is also sufficient to cause the pawls 12 to be pulled out of engagement with the teeth on the bars by the cable 17. As a result the pawl and its lever will drop down to normal position and the eight inches of slack will be restored in the cable 14 and the various parts will be reset. The train will thus be halted with the first car in position ready to enter the cage or the rotary dump provided therefor. The lever 1 on the valve can then be depressed manually or otherwise far enough to operate the engine and release the cars from the horns H so that the train promptly moves forward and the first car of the train enters the cage or dump. This movement of the train operates the bar 8 as hereinbefore described, taking up the slack by successive operations so that, as the second car of the train enters the cage or dump the parts will again be operated automatically to elevate the horns H and stop the train. The dump or cage is then operated. Thus each time the lever 1 is operated in one direction the train is released and after the desired number of cars have passed into the cage or dump, the train will be automatically checked in its movement until again released. Obviously by increasing or reducing the slack in the cable 14 the number of cars delivered for simultaneous emptying can be increased or diminished.

As shown in Figures 1 and 2 stop mechanism can be located at a suitable point beyond the delivery end of the rotary dump A, this mechanism being indicated generally at D and including horns F similar to the horns H, which are provided with toggles G and an arm G', this arm being connected by a rod R' to the engine E. Obviously, therefore, as the cars emerge from the dump A the first car of each pair (if the cars are being dumped in pairs) will be stopped by the horns F and held elevated, as shown so that when the engine is operated to release the cars at the loading side of the dump the cars at the delivery side will also be released, all of the horns at both sides of the dump operating in unison.

By providing the spaced horns H sufficient distance can be left between the stop mechanism for a scales on which the cars can be successively weighed before being directed into the dump.

What is claimed is:—

1. The combination with a track leading to car moving apparatus, of car holding means adjacent the track, means for shifting said holding means to release a train of cars upon the track, power operated means for shifting said holding means to active position, and means operated by successive cars

approaching the car moving apparatus for automatically applying power to the power operated means to stop the movement of the cars along the track.

5 2. The combination with a track leading to car receiving means, of car holding means, means for shifting the holding means to release a train of cars upon the track, and power operated means controlled by the action of successive cars approaching the receiving means, for stopping the movement of the train of cars along the track.

10 3. The combination with a track leading to car receiving means, of car holding means, means for shifting the holding means to release a train of cars upon the track, power operated means for moving the holding means to stop the movement of the train of cars along the track, lever controlled means 15 for directing power to said power operated means, a normally slack power transmitting element connected to said lever controlling means, and means adapted to be engaged and operated by successive cars moving 20 along the track for taking up the slack in said element and shifting the lever controlled means to apply power and stop the train.

25 4. The combination with a track leading to car receiving means, of car holding means, means for shifting the holding means to release a train of cars upon the track, power operated means for moving the holding means to stop the movement of the train of cars along the track, power controlling valve 30 mechanism, a lever for operating the same, a tripping arm adapted to be successively depressed by cars passing successively there-over, a normally slack power transmitting 35 element connected to the lever of the valve mechanism, and means operated by the successive movements of the tripping lever for taking up the slack in said element and operating the valve mechanism to direct power to the power operated means and stop the movement of the train of cars.

40 5. The combination with car holding means and means for shifting the holding means to release a train of cars, of parallel

fixed and movable toothed bars, a tripping 50 arm adapted to be repeatedly depressed by cars passing successively, means operated by each depression and release of the tripping arm for shifting the movable toothed bar up and down, a lever, pawls carried thereby and 55 engaging the toothed bars, said movable bar operated to elevate the pawls and lever step by step relative to the fixed bar, means operated by the pawls when shifted to a predetermined position for automatically elevating the holding means to stop the cars, and means operated by said last named action for disengaging the pawls from the fixed bar and resetting the pawls.

6. The combination with car holding 65 means, of power operated means for moving the holding means to stop the movement of a train of cars, a power controlling valve mechanism, a lever for operating the same, a tripping arm adapted to be repeatedly depressed by cars passing successively there-over, a normally slack power transmitting 70 element connected to the lever of the valve mechanism, and means operated by the successive movements of the tripping lever for 75 taking up the slack in the said element and operating the valve mechanism to direct power to the power operated means and stop the movement of the train of cars.

7. The combination with a valve operating lever, of parallel fixed and movable toothed bars, a power transmitting lever, pawls carried thereby for engaging the teeth on the bars, a slack flexible connection between one end of said lever and one arm 80 of the valve operating lever, a flexible connection between another arm of the valve operating lever and the pawls, a car actuated tripping arm, and means for transmitting motion from said arm to the movable bar. 85 90

In testimony that I claim the foregoing as my own, I have hereto affixed my signature in the presence of two witnesses.
